UNITED STATES PATENT OFFICE.

HENRY B. WOODS, OF SAN FRANCISCO, CALIFORNIA.

SHOE-LACING DEVICE.

1,022,808.

Specification of Letters Patent.

Patented Apr. 9, 1912.

Application filed August 29, 1911. Serial No. 646,584.

To all whom it may concern:

Be it known that I, HENRY B. Woods, citizen of the United States, residing in the city and county of San Francisco and State 5 of California, have invented new and useful Improvements in Shoe-Lacing Devices, of which the following is a specification.

This invention relates to shoe fastening devices, and particularly to flexible lacings. 10 The object of this invention is to provide a simple, durable, inexpensive and readily tightened or loosened lacing which is without knots, tips and special metallic attachments; and particularly to provide a lace 15 devoid of unsightly features, and which is so laced that the foot cannot slide or jam down into the toe of the shoe, leaving the tongue straight and smooth.

An important object is to provide a lacing 20 in which the pressure is distributed entirely around the ankle so as to strengthen and support it so that the edges of the vamp cannot cramp the instep and also leaves the cords of the ankle free and easy.

25 The invention consists of the parts and the construction and combination of parts as hereinafter more fully described and claimed, having reference to the accompanying drawings, in which—

30 Figure 1 is a perspective of the lacing and shoe partly tightened. Fig. 2 shows the shoe after lacing. Fig. 3 shows the stay which holds the lace in place. Fig. 4 shows a shoe with a single lace. Fig. 5 shows the shoe 35 before tightening the lace. Fig. 6 shows a lace with free ends.

In practicing my invention, I employ a suitable, endless or other lace 2 of sufficient 40 length to band around the ankle and vamp 3 of the shoe 4; then go forward and through an eyelet of a hook on each side; thence down between the vamp and the shoe tongue and out through the second eyelet from the bottom; thence across and through the lower 45 eyelet on opposite side; then back and out the same second eyelet thus forming a double cinch; then being appropriately laced up the several eyelets and forming over the instep and preventing the foot from sliding

down into the shoe; loose, right-hand and 50 left-hand tightening strands 6 and 7 which extend to the rear of the shoe and cross over a stay 8 Fig. 3.

It is understood that this lacing may be used in any boot or shoe having a series of 55 eyes or eyelet hooks.

To more fully explain the salient features of the invention the details are particularly described hereinafter.

While the lace may consist of a single 60 lace, in order to assist in explanation the several connected parts will be designated with names and numerals for identification only.

Fig. 5 very clearly shows the shoe with 65 the lace 2 correctly laced and in readiness to be laced up the hooks 9. In threading the lace, before it is united at its ends, it is passed transversely beneath the upper end of the stay 8 of the shoe. The stay is so 70 stitched that it is possible to pass the lace from side to side, as at 10, between the stay and the back of the vamp. The lace is then carried around both sides of the latter to the front of the shoe forming a band 11 75 bearing snugly upon the vamp. Thence the lace ends, which may be drawn even in front of the shoe, are passed through suitable of the eyelet hooks, as at 12, and down between the vamp edges 13—14 and the tongue from 80 beneath which they are then brought up through the second lowest eyelets as at 15 Fig. 1. This creates the straight stretches 17 dotted on each edge of the vamp. The ends are then crossed over and down through the 85 lowermost eyelets; then up and across to the second eyelet forming a loop or double cinch.

The as yet disconnected ends of the lace are then laced zig-zag, as in Fig. 1, or plain at 18 Fig. 4. From the uppermost eyelets 90 5 the lace ends are then carried back around the vamp, Figs. 3 and 5; the right-hand portion being passed out through an opening 19 and then diagonally up to and through an opening 20 in the stay; thence being 95 passed under the band 11. The left-hand portion of the lace, Fig. 3, is passed out through an opening 21 and diagonally over

the stay, inwardly through a perforation 22 and beneath the band 11.

The ends may, if desired, be united as shown, or the ends can be left hanging loose 5 as in Fig. 6. However, while I have described one method of lacing the lace 2 it is understood that any method may be pursued which will result in obtaining the proper end, and, therefore, no point of union 10 of the lace ends is indicated as this would vary with the method adopted to lace the shoe.

When the lace is properly threaded there 15 are formed the band 11 around the vamp and beneath the stay, the extensions 18 along the edges of the vamp, the primary lacings 15 and the two tightening strands 6 and 7, the former on the right and the latter on the left. These strands continue around to 20 the rear of the vamp and cross at 25 over the stay 8, eventually uniting in a pull or draw-loop 26.

Referring to Fig. 5 which shows the shoe unlaced, it will be observed that the strands 25 6—7 are of sufficient length to allow the edges of the vamp to spread well apart as the foot is inserted in the shoe. As the edges of the vamp move apart the strands will freely travel through the eyes 5, and 30 when the shoe is fitted a pull on the strands draws the slack from the eyelets, after which the strands may be laced up as shown in Fig. 2.

Since the extensions 17 of the band 11 35 follow down their respective edges of the vamp and do not cross except near the lower, front portion of the vamp the edges of the latter can be folded open or out over the instep without restriction by the extensions 17 or the strands 6 and 7.

When the foot is in the shoe and the strands laced up all slack is taken from each by a pull on the loop 26 which draws the slack over the stay, as at 25, and beneath 45 the band 11. Pulling on the loop 26 tightens the vamp around the ankle and over the instep with equal circumferential pressure, and while the foot is embraced snugly yet it is not pinched by pressure as usual by the 50 common lacing.

The stay 8 helps to bind or hold the lace in position, but the peculiar under and cross-lacing of the latter in the stay is what 55 accomplishes the clamping of the lacing, making it impossible for it to slip or become unfastened. When the shoe is to be removed a downward pull on the strands at a Fig. 2 quickly takes up the loop 26 and the lacing in the front of the shoe may be 60 undone.

It will thus be seen that I have provided a durable, comfortable, double lace which 65 will allow the ankle and cords to move without injurious pinching or pressure and there is no danger of the lace becoming acciden-

tally unfastened and dangling around the foot.

Having thus described my invention, what I claim and desire to secure by Letters Patent is—

1. In a shoe, a vamp having eyelets and eyelet hooks, a stay on the back of said vamp, and a lace having a part girdling the vamp and passing beneath the stay; thence extending forwardly and down through eyelets of said hooks and between the edges of the vamp and the tongue of the shoe and threaded in the eyelets of the lower part thereof; thence continuing up in tightening strands on the side of the shoe and to 80 the rear.

2. In a shoe, a vamp having eyelets and eyelet hooks, a stay on the back of said vamp having perforations, and a lace having a part girdling the vamp and passing beneath the stay; thence extending forwardly and down through eyelets of said hooks and down the adjacent edges of the vamp and the tongue of the shoe and threaded in the eyelets of the lower part thereof; thence continuing up in tightening strands on the side of the shoe and to the rear, said strands being passed through the perforations in and crossed over the stay and then locked beneath the girdling part 95 at the rear of the vamp.

3. In a shoe, a fastening lace, a vamp having eyelets and eyelet hooks, said lace having a band portion encircling the rear of the vamp, stretches extending down through eyelets of said hooks under the vamp edges and being laced through eyelets therein, and tightening strands engageable with hooks of the shoe.

4. In a shoe, a fastening lace, a vamp having eyelets and eyelet hooks, said lace having a band portion encircling the rear of the vamp, stretches extending down through eyelets of said hooks and being laced through eyelets therein, and tightening strands engageable with hooks of the shoe.

5. In a shoe, a vamp having eyelets and eyelet hooks, a stay on the back of the vamp having perforations, and a lace threaded in the perforations in the stay and running around the sides of the vamp and through eyelet hooks; thence down beneath and adjacent to the vamp edges, passing out through eyelets adjacent to the lower portion of the vamp, the lace then being looped through the lower diagonally opposite eyelets to form a double cinch; thence being laced up through the upper eyelets and having tightening strands engageable with the 125 eyelet hooks.

6. In a shoe, a vamp having eyelets and eyelet hooks, a stay on the back of said vamp having a plurality of upper and lower perforations, a lace having a section 130

threaded through the eyelets, and tightening strands extending from the uppermost eyelets and around to the back of the shoe, thence passing out of lower perforations in the stay and crossing same, and being threaded through the upper perforations to form a draw loop.

In testimony whereof I have hereunto set my hand in the presence of two subscribing witnesses.

HENRY B. WOODS.
